UNITED STATES PATENT OFFICE.

LOUIS KELLNER, OF BROOKLYN, NEW YORK.

ELECTRIC LAMP.

Application filed November 29, 1921. Serial No. 518,715.

To all whom it may concern:

Be it known that I, LOUIS KELLNER, a citizen of the United States, and resident of the borough of Brooklyn, county of 5 Kings, city and State of New York, have invented certain new and useful Improvements in Electric Lamps, of which the following is a specification.

This invention relates to means for preventing unauthorized removal of electric lamps, screw plug connectors and similar devices, from their threaded sockets or receptacles. The ordinary electric incandescent lamp is provided with a threaded base 10 or plug which engages a correspondingly threaded metal shell in a socket or receptacle, and various other forms of electrical connectors are similarly equipped with threaded bases for the purpose of securing 15 them in threaded sockets. This invention is applicable to all of these devices, and while I have illustrated it as applied to incandescent lamps, it will, of course, be understood that it may be applied to the 20 other forms of screw connectors.

Electric incandescent lamp bulbs are frequently stolen because they may be readily removed from their sockets by merely unscrewing them. The purpose of this invention, as applied to lamps of this character, is to provide means whereby the lamp may be 30 threaded into the ordinary lamp socket, but which when in place cannot be readily removed without the insertion of the properly 35 shaped key.

The main object of this invention is to provide a device of the character described which shall be simple to manufacture, but which is effective in operation, and which 40 will not require any change in the ordinary standard lamp socket.

In the drawing, Fig. 1 is a side elevation of an incandescent lamp bulb partly in section and showing the invention applied 45 thereto;

Fig. 2 a side elevation of the threaded connector sleeve;

Fig. 3 a similar view of the insulating guard flange; and

50 Fig. 4 a detail perspective view of the key designed to connect the connector sleeve to the lamp bulb.

Referring to the various parts by numerals, 1 designates the lamp bulb. To the reduced terminal end of the bulb is rigidly 55 connected the usual insulating plug extension 2 through which the terminal wires extend. On the outer end of the plug extension is rigidly mounted a contact plate 3 to which one terminal wire 4 is connected. Surrounding the plug extension 2 is a cylindrical metal terminal shell 5; and to this shell one end of the terminal wire 6 is connected. One end of the terminal shell is 60 slightly enlarged to receive the reduced terminal end of the bulb, and the shell is secured to the plug extension and to the bulb by suitable cement. The free end of the terminal shell 5 is bent outwardly to form the annular radial flange 7, said flange 65 being at the free end of the plug extension and near the contact 3.

Surrounding the terminal shell and loosely rotatable thereon is a threaded connector sleeve 8; one end of said sleeve being close 75 to the flange 7 and the other engaging or fitting closely to the enlarged end of the terminal shell. The sleeve 8 is externally threaded and is of standard size to adapt it to be screwed into the internally threaded 80 standard lamp socket. The end of the connector sleeve adjacent the lamp bulb is formed with a cylindrical or unthreaded part 9; and between the flange 7 and the adjacent end of the sleeve 8 is arranged a loose ring or washer 10. Secured to the lamp body and the enlarged end of the terminal sleeve is a guard flange 11 of insulating 85 material, said flange surrounding and enclosing the cylindrical extension of the connector sleeve. The guard flange is so located that there is a very slight longitudinal play between the threaded connector sleeve, the washer 10 and the guard flange; and the connector sleeve is so arranged that there will at all times be an 90 electrical contact between it and the terminal shell 5.

In the guard flange a C-shape opening 12 is formed; and in the cylindrical extension 100 of the connector sleeve a similar opening 13 is formed. By rotating the lamp plug and the guard flange with respect to the connector sleeve, these two C-shape open-

ings may be brought into register, and a connector key 14 may then be inserted through the guard flange and the connector sleeve to thereby lock the sleeve to the lamp bulb so that by turning the lamp bulb it may be threaded into or out of its socket. Connected to the key 14 is a finger piece 15 of any suitable insulating material.

- When it is desired to thread the lamp in
- 10 an ordinary standard lamp socket, the key 14 is passed through the registering openings in the guard flange and the connector sleeve. This locks the sleeve to the lamp bulb and the lamp may be threaded into its
- 15 socket in the usual way. When the lamp is screwed home and its contacts are in engagement with the usual contacts of the socket the key may be removed. This frees the connector sleeve and the lamp may then
- 20 be turned freely without unscrewing the connector sleeve from the socket. In order to remove the lamp from its socket, the openings in the guard flange and the connector sleeve must be brought into register
- 25 and then the key 14 inserted. The purpose of securing an insulating finger piece to the key is to prevent the operator from receiving the electric current from the connector sleeve. It is manifest that if it be
- 30 attempted to connect the connector sleeve with the guard flange by inserting a small piece of metal, a piece of wire or a pin, the operator will receive the current from the lamp circuit.
- 35 The purpose of the washer 10 is to prevent any possibility of the friction between the end of the connector sleeve and the retaining flange 7 being sufficient to lock the connector sleeve to the plug. The guard flange
- 40 11 prevents access to the connector sleeve when the lamp is screwed in its socket and also prevents any accidental contact with the extension of the connector sleeve when manipulating the lamp either to insert it
- 45 or withdraw it from its socket.

What I claim is:

1. An incandescent electric lamp comprising a bulb, an extension of insulation secured to the terminal end of said bulb, a
- 50 terminal extending through said insulation, a contact on the end of the insulation and connected to the terminal, a cylindrical terminal shell surrounding the said extension and rigidly connected thereto, a terminal
- 55 wire connected to said shell, a threaded sleeve loosely surrounding and rotatable on the terminal shell and in electrical contact therewith, means at the outer free end of the terminal shell to retain the threaded
- 60 sleeve in position, an insulating ring carried by the lamp and enclosing the adjacent end of the threaded sleeve, and removable means for connecting the threaded sleeve to the lamp to turn therewith.
- 65 2. An electric lamp comprising a bulb, a

loosely rotatable threaded sleeve of conducting material mounted on the terminal end thereof and adapted to screw into a lamp socket, a ring of insulating material secured to the lamp and fitting over the end of the sleeve adjacent the lamp bulb, means for temporarily locking the sleeve to the lamp to turn therewith, and contacts carried by the lamp.

3. An electric lamp comprising a bulb, a

75 loosely rotatable threaded connector sleeve of conducting material mounted on the terminal end thereof and adapted to screw into a lamp socket, a guard flange of insulating material secured to the lamp and fitting

80 over the end of the connector sleeve adjacent the lamp bulb, and removable means adapted to be inserted through the insulating guard flange and the connector sleeve for temporarily locking the sleeve to the lamp to turn therewith, and contacts carried by the lamp and adapted to engage contacts in the lamp socket.

4. An electric connector adapted to fit a

90 threaded socket and comprising a rigid plug carrying two terminal wires, a loosely rotatable threaded connector sleeve of conducting material mounted on said plug and adapted to screw into a threaded socket, a guard flange carried by the connector and rotatable with the plug relatively to the connector sleeve said guard flange fitting over and enclosing the adjacent end of the connector sleeve and serving as a cover and protector for said sleeve when the connector

95 is in place in its socket, and a removable means adapted to be inserted through the guard flange and the connector sleeve to temporarily lock the sleeve to the lamp to turn therewith.

5. An electric connector adapted to fit a

100 threaded socket and comprising a rigid plug carrying two terminal wires, a loosely rotatable threaded connector sleeve of conducting material mounted on said plug and adapted to screw into a threaded socket, a guard flange of insulating material carried by the connector and rotatable with the plug relatively to the connector sleeve said guard flange fitting over and enclosing the adjacent end of the connector sleeve and serving as a cover and protector for said sleeve when the connector is in place in its socket, the guard flange and the enclosed end of the connector sleeve being formed with openings adapted to be brought into register, and a removable key adapted to be passed through said openings to temporarily lock the connector sleeve to the guard flange.

6. An electric connector adapted to fit a

115 threaded socket and comprising a rigid plug carrying two terminal wires, a loosely rotatable threaded connector sleeve of conducting material mounted on said plug and adapted to screw into a threaded socket, a

120

guard flange of insulating material carried by the connector and rotatable with the plug relatively to the connector sleeve said guard flange fitting over and enclosing the adjacent end of the connector sleeve and serving as a cover and protector for said sleeve when the connector is in place in its socket, the guard flange and the enclosed end of the connector sleeve being formed with open-

ings adapted to be brought into register, a 10 removable key adapted to be passed through said openings to temporarily lock the connector sleeve to the guard flange, and an insulating finger piece secured to said key.

In testimony whereof I hereunto affix my 15 signature.

LOUIS KELLNER.
